(57) **CLAIM**

The ornamental design for an electronic hookah, as shown and described.

DESCRIPTION

FIG. 1 is a front view of an electronic hookah according to the present application;

FIG. 2 is a rear view of the electronic hookah according to the present application;

FIG. 3 is a left view of the electronic hookah according to the present application;

FIG. 4 is a right view of the electronic hookah according to the present application;

FIG. 5 is a top view of the electronic hookah according to the present application;

FIG. 6 is a bottom view of the electronic hookah according to the present application;

FIG. 7 is a first perspective view of the electronic hookah according to the present application; and,

FIG. 8 is a second perspective view of the electronic hookah according to the present application.

The broken lines in the drawings illustrate portions of the electronic hookah which form no part of the claimed design.
